UNITED STATES PATENT OFFICE.

CARL AXEL WILHELM HULTMAN, OF DJURSHOLM, SWEDEN.

SELECTOR.

Application filed May 16, 1922. Serial No. 561,413.

To all whom it may concern:

Be it known that I, CARL AXEL WILHELM HULTMAN, chief engineer, subject of the King of Sweden, residing at Djursholm, Sweden, have invented certain new and useful Improvements in Selectors, of which the following is a specification.

This invention relates to improvements in selectors of the type used in automatic telephone systems as described in my prior United States Patent No. 1,431,116. The movements of such a selector are controlled by an impulse sender preferably attached to the selector itself and by an impulse receiver such as known registers controlled by the impulses conveyed. The invention has for its object to increase the safe operation of similar systems by decreasing the number of impulses necessary to set the register to half the number of positions of said selector. For this purpose the arrangement of the selector is such that it sends impulses only at every second position, while the register moves one step at the closing and a further step at the opening of the impulse circuit.

The invention will be further described with reference to the accompanying drawing, in which—

30 Figs. 1^a and 1^b show a simplified wiring, and

Fig. 2 shows the impulse receiver.

In the embodiment shown in Fig. 1 the selector is assumed to be provided with an impulse sender comprising an impulse medium IS moving with the selector and a contact spring IK co-operating with the impulse medium, which latter consists of a contact bar running in the direction of the selector's movement, in case this is linear, or of a disc adapted on the rotating shaft of the selector, in case this latter one rotates. The contact spring IK is actuated by projections IT in the bar IS of a number half of that of the positions of the selector, that is at the positions 1, 3, 5, and so on. The selector is also provided with a stop-work consisting of a stop-bar SS provided with rectangular notches and a catch SH. The stop-work is so designed as to stop the selector at each position 1, 2, 3, and so on.

It is assumed that the selector in this case is of the machine-driven type. The connecting and disconnecting of the selector is accomplished in a known manner by means

of an electromagnet KM. The setting of the selector is controlled by a number of register switches RS₁, RS₂, corresponding to the figures of the different subscribers, and a number of impulse receivers IM₁, IM₂. The register switches are set in a known manner from the subscriber's or the operator's place in correspondence to the wanted subscriber's figure. The impulse receivers on the other hand are set by impulses sent from the selector with the aid of an impulse-relay IR. RK₁ and RK₂ are the sets of contacts belonging to the register-switches, and IK₁ and IK₂ are the sets of contacts belonging to the impulse receivers. The sets of contacts RK₁, RK₂ and IK₁ are connected to one another as shown in the drawing, while the set IK₂ is connected to other register switches not shown. In the embodiment shown the selector is assumed to have 25 setting positions in the first direction of movement, causing the impulse receiver to be provided also with 25 contacts, divided in three groups. The sets of contacts for the register switches and the impulse receivers comprise contact-bars KS₁—KS₅, against which the movable contacts slide in such way that these bars at every setting position are electrically connected to the contact which corresponds to the setting position in question.

The design of the impulse receivers is shown in Fig. 2. The movable contacts SK are connected to a rotatable shaft VA carrying a catch-segment ST with notches co-operating with a double-catch DH. This catch is rotatable around a pin HT and is actuated by a spring HF in such way that the segment ST normally is caught by one tooth of the double-catch. The double-catch is actuated by a magnet IM through the armature MA rotatable at MT. The movement of the contact SK is performed by the helical spring KF, which is attached to the stand MS with one end, and with the other end to and wound around a roll FR fixed to the shaft VA, the said spring thereby striving to turn the contacts KS out of the normal position shown in the drawing into the direction indicated by the arrow.

When the electromagnet IM attracts its armature the catch-segment ST is released by the one tooth of the catch DH, whereby the contact springs SK through the action of the spring KF are moved forward one

step to the next contact spring and are there caught by the other tooth of the catch DH. When the electromagnet IM then releases its armature, the catch DH is caused to return to its original position, whereby the contact springs SK are moved forward another step to the next contact position where they are caught by the catch DH. In this manner the contacts SK are moved forward one step for each closing and another step for each opening of the circuit by the electromagnet IM. Since the movable contacts are set the resetting of same is accomplished by a special resetting mechanism not shown, which acts upon the projection AV of the catch-segment ST so that this latter one is moved back to its normal position.

Since the setting of the register switches RS₁, RS₂ and so on has been accomplished, the setting of the selector is performed in the following manner. The contacts SO₁, SO₂, SO₃ are first closed through the action of a sequence switch not shown; or the like, as generally used for controlling the connections in an automatic telephone exchange with machine driven selectors. Thereby a circuit 11 is closed through a stop magnet SM, which attracts its armature causing the catch SH to release. The catch SH thereby closes a circuit 12 over the magnet KM causing the selector to start. During the movement impulses of currents are sent out at every second setting position over the circuit 13 including the impulse relay IR. This latter one closes and opens in accordance thereto a local circuit 14 for the impulse receiver IM₁, which thus is set step by step, until its movable contacts reach a contact making position, when a circuit 15 is closed over the contacts in the register switches, upon which these latter ones are set. In the circuit 15 a stop relay SR is connected, which now comes in action and opens the circuit 11, thereby causing the stop magnet SM to release its armature and the catch SH. The circuit 12 for the selec-

tor's coupling magnet KM remains closed until the catch SH has reached its catching position in a notch in the bar SS, whereby the contact K₁ is opened, the magnet KM disconnected, and the selector stopped. When the relay SR attracts its armature it connects itself into a holding circuit over the contact K₂ and acts upon a contact K₃ which causes the impulse receiver IM₁ to be released and the impulse receiver IM₂ to be connected to the local circuit influenced by the impulse relay IR. At the next movement of the selector its impulses are received by the impulse receiver IM₂, which thereby is set in the same way as the impulse receiver IM₁, and the selector is set in the manner above described.

Should the stop relay SR become actuated in such position of the impulse receiver which corresponds to a circuit closing through its electroinagnet, the circuit will immediately become opened by this electroinagnet at the contact K₃, whereby the movable contacts of the impulse receiver are moved forward another step. Thereby the circuit 15 certainly will become opened but the stop relay SR is nevertheless kept alive over the contact K₂, so that a renewed starting of the selector is prevented.

What I claim as new and desire to secure by Letters Patent of the United States of America is:—

In automatic or semi automatic telephone system is a selector having an impulse sending device, a register responsive to impulses from said device and governing the advancement of said selector, the impulse sending device being so arranged that a new impulse is sent out only at every second position of the selector and the register is moved one step at the closing and another step at the opening of said impulse circuit.

In testimony whereof I affix my signature.

CARL AXEL WILHELM HULTMAN.
